UNITED STATES PATENT OFFICE

GEORGE A. CARTER AND MADISON G. TILLERY, OF ENID, OKLAHOMA

WOOD-SAWING MACHINE

Application filed September 24, 1929. Serial No. 394,840.

This invention relates to wood sawing machines and more particularly to machines of this character of the rotary saw type wherein the saw is associated with an actuating motor on a supporting mechanism for permitting the saw to be shifted or adjusted to different positions for performing different kinds of work.

An important object of the invention is to provide, in a manner as hereinafter set forth, a wood sawing machine of the aforementioned character comprising a power driven rotary saw and the driving motor therefor which are mounted on a support of a construction which will permit the saw to be expeditiously adjusted and secured in any desired position or at any angle with respect to the work and wherein the construction of the support is such that it may be secured to any desired base such as a floor, vertical wall or a ceiling and will operate with efficiency when so mounted.

Other objects of the invention are to provide a wood sawing machine of the aforementioned character which will be simple in construction, strong, durable, efficient in its use and which may be manufactured at low cost.

Other objects and advantages of the invention will become apparent from a study of the following specification, taken in connection with the accompanying drawings wherein like characters of reference designate corresponding parts throughout the several views, and wherein:

Figure 1 is a front elevation of a wood sawing machine constructed in accordance with this invention,

Figure 2 is a view in side elevation thereof, Figure 3 is a front elevation illustrating the wood sawing machine in one of its adjusted positions,

Figure 4 is a front elevation of the machine showing the saw adjusted to a position at right angles to the position shown in Figure 1,

Figure 5 is a fragmentary view, partly in section, showing the upper portion and the rod which secures the saw hanger in adjusted

position, and the socket into which said rod is inserted,

Figure 6 is a fragmentary view in vertical section of the means for adjusting the saw vertically on the standard and taken substantially on the line 6—6 of Figure 2.

Referring to the drawings in detail, the reference character 1 designates a substantially bell shaped base from which extends a vertical tubular standard 2 of uniform diameter throughout. A laterally projecting arm 3 is slidably mounted for longitudinal movement on the upper portion of the standard 2 through the medium of a sleeve 4 formed on one end of said arm which encircles the standard.

Intermediate its ends, the standard 2 has extending laterally therefrom a bracket 5 having an upturned end portion provided with a journal 6 in which is mounted a rotatable crank 7. The shaft of the crank 7 extends through the journal 6 and terminates in spaced relation to the standard 2 and has mounted thereon a beveled gear 8.

A screw shaft 9 which parallels the standard 2 has its lower end journaled in the horizontal portion of the bracket 5 and has rigidly mounted thereon a beveled gear 10 which meshes with the gear 8. A laterally extending lug or ear 11 is mounted on the sleeve 4 in superposed relation with respect to the bracket 5 and is provided with a threaded bore extending vertically therethrough for threaded engagement with the screw shaft 9.

It will thus be seen that the arm 3 may be expeditiously and accurately adjusted on the standard 2 by actuating the crank 7 and rotating the screw shaft 9 through the medium of the gears 8 and 10 for causing the threaded lug 11 to move vertically on said screw shaft. A set screw 12 is threaded through the sleeve 4 for engagement with the standard 2 for the purpose of securing the arm 3 in adjusted position thereon.

At its free end, the arm 3 is provided with a flat disc shaped head 13. A coupling bracket 14 is provided with a vertically disposed flattened face 15 for engagement with the head 13 and is rotatably coupled thereto through the medium of a pivot bolt or pin 100

16, shown most clearly in Figures 1 and 4 of the drawings.

The coupling bracket 14 is further provided with a horizontally disposed flattened face 17 extending outwardly at right angles to the base 15. A flat disk shaped head 18 abuts the lower flat side of the face 17 of the coupling bracket 14 and is rotatably connected thereto. Reinforcing webs 19 connect the portions 15 and 17 of the coupling bracket. It will thus be seen that the coupling bracket 14 is adapted to rotate in a vertical plane on the head 18 of the arm 3 and the disc or head 18 is adapted to rotate in a horizontal plane on the portion 17 of said coupling bracket.

A lever operated detent 20 is mounted on each of the portions 15 and 17 of the bracket 14 and said detents are adapted to project into registering openings in the adjacent portion 20 of the bracket and heads 13 and 18 for the purpose of securing same in adjusted position with respect to each other.

The swivel head 18 has connected thereto a pair of outwardly and downwardly extending arms 21 in the lower end portions of which the opposite ends of a horizontal shaft 22 are mounted. A saw hanger or arm 23 is suspended from the shaft 22 in a manner to swing thereon through the medium of base 30 apertured arm 24 on the upper end of said hanger through which the shaft 22 extends.

A mandrel 25 is journaled in the lower end of the hanger 23 and extends laterally beyond the opposite sides thereof and has mounted 35 on one end a circular saw 26. The opposite end of the mandrel 25 has mounted thereon a pulley 27. An electric motor 28 is mounted on the hanger 23 adjacent its upper end and a drive pulley 29 is mounted on the shaft 30 of said motor.

An endless drive belt 31 is trained over the pulleys 29 and 27 for rotating the saw 26 when the motor 28 is in operation.

A safety guard 32 is mounted on the 45 hanger 23 and extends in front of the belt 31 and a guard 33 protects the operator from the saw 26.

As before stated the hanger 23 with the saw 26 and motor 28 thereon is adapted to swing on the shaft 22 and in order to secure said hanger in a manner to prevent the swinging of same on said shaft when it is so desired, a pair of laterally extending apertured arms 34 are mounted thereon through which extends a vertical rod 35 the upper end of which is adapted to be inserted in a socket 36 formed in a depending portion 37 of the head 18.

The lower end of the rod 35 is clamped in a sleeve 38 through the medium of a set screw 39 and said sleeve is provided with a lateral extension 40 which projects through an elongated slot 41 in the hanger 23. The portion of the extension 40 which extends through the slot 41 is externally threaded and of less diameter than the portion of the arm 40

which is rearwardly of the hanger 23 and a shoulder is thus provided which engages the adjacent base portion of said hanger 23 on opposite sides of the slot 41. A clamping nut 42 is threaded on the end of the arm 40 and is of greater width than the slot 41. It will thus be seen that when the clamping nut 42 is threaded inwardly on the arm 40, said arm will be frictionally clamped on the hanger 23 at any desired point between the ends of the slot 41.

It will thus be seen that I have provided a wood sawing machine wherein the rotary saw may be set at any desired angle and secured in its adjusted position. The slideable connection of the arm 3 on the standard 2 permits vertical adjustment of the saw. The connection provided by the head 13 and the portion 15 of the coupling bracket 14 permits lateral swinging of the saw, as shown in Figure 3 of the drawings.

The connection between the head 18 and the portion 17 of the coupling bracket 14 permits rotary adjustment of the saw as seen in Figure 4 of the drawings. The swinging connection of the hanger 23 on the shaft 22 permits the saw to be swung in a vertical plane, as will be apparent. For the purpose of shifting the saw when the device is in operation, a handle 43 is mounted on the hanger 23 adjacent its lower end.

A switch 44 is also mounted on the hanger 23 for controlling the flow of current through the motor 28.

It is to be understood that any other type of woodwork cutter may be mounted on the mandrel 25 in the place of the rotary saw 26, such as a dado cutter. It is believed that the many advantages of a wood sawing machine constructed in accordance with this invention will be readily understood, and although the preferred embodiment of the invention is as illustrated and described, it is to be understood that changes in the details of construction may be had which fall within the scope of the invention as claimed.

What is claimed as new is:

1. A wood sawing machine of the character described comprising a standard, a laterally extending arm slidably mounted on the standard, coating means on said standard and the arm for shifting the latter longitudinally thereof, a coupling bracket connected for rotation in a vertical plane to the free end of the arm, a supporting element connected for rotation in a horizontal plane to the coupling bracket, a saw hanger swingingly suspended from the supporting element, a rotary saw mounted on the saw hanger, means for rotating said saw and means for locking the adjacent elements together to prevent relative movement therebetween.

2. A wood sawing machine of the character described comprising a vertical standard, a horizontal arm slidably mounted on the

standard, means for shifting said arm on the standard, and means for adjustably coupling a saw to the free end of said arm comprising a flat vertically disposed head on the arm, a coupling bracket having a flat vertically disposed face for engagement with the head, means for rotatably coupling the bracket to the head, said coupling bracket being further provided with a flat horizontally disposed face portion at right angles to the vertical portion, a flat horizontally disposed head rotatably connected to the last named portion of the coupling bracket, depending arms connected to the horizontal head, a horizontal shaft supported in the lower end portions of said arms, a saw hanger swingingly mounted on the shaft at one end and having a rotary saw journaled therein at its opposite end and means for securing the saw in adjusted position on the arm.

3. A wood working machine of the character described comprising a vertical standard, a horizontal arm adjustably mounted on the standard, a coupling bracket rotatably connected to the free end of the arm, a supporting element rotatably connected to the coupling bracket, and a saw hanger swingingly connected to the supporting element and having means thereon for preventing swinging of the hanger on the supporting element and comprising a socketed extension extending from the supporting element, an elongated rod slidably mounted for vertical movement on the hanger and adapted for insertion in the socket, and means adjacent the lower end of the rod adjustably anchoring the same to the hanger.

In testimony whereof we affix our signatures.

40 GEORGE A. CARTER.
MADISON G. TILLERY.
